Primary Examiner — Jennifer L Watkins

(57) **CLAIM**

I claim the ornamental design for the interior ankle brace, as shown and described.

DESCRIPTION

FIG. 1 Is a perspective view of the interior ankle brace.

FIG. 2 Is a side view of the interior ankle brace.

FIG. 3 Is an additional side view of the interior ankle brace.

FIG. 4 Is a top view of the interior ankle brace.

FIG. 5 Is a bottom view of the interior ankle brace.

FIG. 6 Is a front view of the of the interior ankle brace; and, FIG. 7 Is a back perspective view of the interior ankle brace. The broken lines found on this interior ankle brace represent brand logos and shoelaces and are not a part of the claimed design.
